UNITED STATES PATENT OFFICE

MERRITT E. CURTISS, OF PITTSBURGH, PENNSYLVANIA

ELECTRIC DISPLAY DEVICE

Application filed November 11, 1929. Serial No. 406,231.

The present invention relates to an electric display box.

The object of the invention is to provide a display box, and a poster associated therewith, so constructed and arranged that the effect of movement is imparted to a feature or features of a human or animal face shown on the poster.

A further object of the invention is to provide simple and inexpensive means for securing such effect of motion.

In the accompanying drawings Figure I is an isometric view showing a display box made in accordance with the present invention; Figure II is a vertical sectional view through the display box, looking toward the poster from the rear, and showing the positioning of light sources therein; Figure III is a cross sectional view through the light box; and Figure IV is a cross sectional detail of a translucent figure or window which is to be illuminated, taken on line IV-IV, Figure I.

In the drawings reference numeral 1 designates the light box as a whole, and reference numeral 2 the poster forming the front of the light box. In the specific arrangement illustrated in Figure I of the drawings, the poster 2 carries the representation 3 of a human face, both of the eyes 4 of which are arranged, and are illuminated in such manner, as to impart the effect of motion thereto.

As shown in Figures I and IV of the drawings, each of the eyes comprises an opaque iris 5, which may be the original material of the poster remaining after cutting out the sclera 6 on one or both sides of the iris. The pupil 7 may be cut away, or may be allowed to remain opaque, as desired. Against the rearward face of the poster 2 and covering the window produced by cutting away the sclera 6 is a layer 8 of mica or other suitable glistening translucent material. Upon this material is laid a sheet 9 of less translucent material such as paper. This layer 9 may be delicate-

ly colored to give the appropriate color effect to the sclera 6 of the eye.

Within the box 1, and disposed rearwardly of the poster 2, are a plurality of intermittent light sources, such as electric lamps A, B, and C set in interrupter sockets 10, and receiving current from a circuit 11.

By reference to Figures II and III of the drawings, it will be seen that the light sources are disposed angularly with reference to each of the translucent windows represented by portions of the eyes 4. Thus the light source A is disposed below and slightly to one side of the eyes 4, the light source B is disposed below and to the other side of the eyes 4, and the light source C is disposed further below the eyes 4. Both the eyes as shown, will be illuminated equally by the light source B, and unequally by the light sources A and C.

If light impinges upon the eyes 4 from all three sources simultaneously, and the light sources be all simultaneously intermittent, a winking effect is produced. If, however, the interrupter sockets 10 be so selected as to provide illumination successively, an effect of rolling the eyes will be produced. Thus if the sequential illumination is from source A, then source B, and then source C, one or two sources only providing illumination at any instant the effect will be the rolling of the eyes in one direction. If the sequence be reversed the effect will be the rolling of the eyes in the other direction. It will be readily understood that the angular position of the light sources contributes to this effect of movement.

If the eye of an animal, rather than a human eye, is to be apparently energized, the cut away portion may be of the iris rather than the sclera of the eye. Thus either the pupil or the entire iris of the eye in a picture of a member of the cat family may be cut out and intermittently illuminated in the same manner. If another feature such as the mouth of a human being or animal is to be

apparently energized, the retention of an opaque portion such as the lips in conjunction with translucent teeth will, because of the intermittent illumination, give the effect of opening and closing the mouth. Desirable comedy effects may be obtained in the same manner by means of the association of intermittent light sources with a human or animal nose, part of which is rendered translucent.

In any case the angular positioning of the light is important, in that it contributes to the effect of movement, and renders such apparent movement more natural.

15 What I claim is:

1. In a display device the combination of a poster comprising the representation of a face having a portion of a feature thereof of opaque material and a portion thereof represented by translucent material, with a plurality of intermittent sources of light disposed rearwardly of said poster and at an angle to the feature comprising the translucent material, whereby the intermittent illumination provided by the several light sources imparts the effect of movement to the feature.

2. In a display device the combination of a generally opaque poster comprising the representation of an eye having at least a portion of the eye ball represented by translucent material, with an intermittent light source disposed rearwardly of said poster and lying wholly behind the opaque body of the poster out of alignment with the representation of the eye.

3. In a display device the combination of a generally opaque poster comprising the representation of a face having therein a feature with at least a portion thereof represented by translucent material, with an intermittent light source disposed rearwardly of said poster and spaced a substantial distance from any line extending through the translucent portion perpendicular to the plane of the poster.

4. In a display device the combination of a generally opaque poster comprising the representation of a face having at least a portion of one feature thereof represented by translucent material, with an intermittent source of light disposed rearwardly of said poster and lying wholly behind the opaque body of the poster out of alignment with the feature comprising the translucent material.

5. In a display device the combination of a poster comprising the representation of a face having at least a portion of the feature thereof represented by translucent material with a plurality of intermittent sources of light disposed rearwardly of said poster and at an angle to the feature comprising the translucent material, the various light sources being arranged to provide illumination at different intervals.

6. In a device to display a picture and to lend illusory movement to a portion of the picture, the combination of a partition bearing the picture, a part of the partition and picture located adjacent the portion thereof which is to appear in movement being deleted and backed by a translucent tegument, and a plurality of intermittent light sources spaced angularly to the rear of the said deleted part.

In testimony whereof I have hereunto set my hand.

MERRITT E. CURTISS.
